L. KAUFOLD

ANTITHEFT DEVICE

Filed March 20, 1924

By LOUIS KAUFOLD
New York
Attorneys

UNITED STATES PATENT OFFICE.

LOUIS KAUFOLD, OF SAN FRANCISCO, CALIFORNIA.

ANTITHEFT DEVICE.

Application filed March 20, 1924. Serial No. 700,591.

To all whom it may concern:

Be it known that I, LOUIS KAUFOLD, a citizen of the United States, and a resident of San Francisco, county of San Francisco, 5 State of California, have invented a new and useful Antitheft Device, of which the following is a specification.

The present invention relates to improvements in anti-theft devices for motor vehicles or the like, and its particular object is 10 to provide means in connection with the intake manifold of the internal combustion engine of a motor vehicle for rendering the engine inoperative. For this purpose it is proposed to provide a gate in the pipe ordinarily connecting the intake manifold with the carburetor and to provide means adapted to be operated from the driver's seat for manipulating the gate the 15 latter being adapted to be swung from an inoperative position into an operative position in which it closes the intake port and prevents the charge from reaching the combustion chamber.

20 The preferred form of the invention is illustrated in the accompanying drawing in which Figure 1 shows a perspective view with my anti-theft device in place; Figure 2 a side view of the manifold having my 25 attachment thereon, and Figure 3 a horizontal section taken along lines III-III of Figure 2. While I have shown only the preferred form of my invention, it should be understood that various changes 30 or modifications may be made within the scope of the claims hereto attached without departing from the spirit of the invention.

The manifold (1) is formed in the usual manner presenting two arms (2) communicating with the combustion chamber and a central leg (3) extending downwardly and connecting with a carburetor not shown in the drawing. The downwardly extending leg (3) is provided with a lateral housing 40 (4) providing a chamber (6) communicating with the inside of the leg (3). Where the housing joins the leg a gate (7) is pivoted in the housing, as shown at (8), the gate corresponding in size to the cross section of the leg (3) so that when the gate is lowered no charge can pass through the leg (3) of the manifold. The housing (4) is shaped so that when the gate (7) is pulled into an inactive position by means 45 of the spring (9) it rests against the

housing as shown at (11) and leaves the passage for the charge clear. The spring (9) is secured to the gate (7) by means of a perforated lug (12) and to the remote wall (13) of the housing by means of a 60 perforated lug (14). The pin (8) to which the gate (7) is secured and which is pivoted in the bearings (16) and (17) is provided, outside of the housing, with a handle (18) to which latter a rod (19) is pivotally 65 connected. This rod preferably extends backward through the dashboard and terminates in an eye (21) brought in registry with a perforation (22) in a stationery member (23) when the gate is closed so that the 70 gate may be locked in that position by introducing a suitable locking means such as the padlock (24) through the two perforations (21) and (22).

The manner of using the device will be 75 readily understood from the foregoing description. If the driver wishes to leave his machine he pulls on the rod (19) so as to lower the gate (7) and thereafter locks the rod to the stationary member (23) by 80 means of the padlock (24). Any unauthorized person not in the possession of the key and not knowing about the particular kind of locking means used will try in vain to start the engine, while on the other 85 hand, as soon as the padlock is removed the gate opens automatically due to the action of the spring (9).

I claim:

1. In combination with an internal combustion engine having an intake manifold and a pipe connecting the same with a carburetor, a means for closing said pipe comprising a housing formed integral with and extending laterally from the pipe so 90 as to communicate with the interior thereof, a gate hinged at the point of juncture between the housing and the pipe, a spring connecting the remote end of the gate with the far wall of the housing for normally 95 maintaining the gate inactive and a handle associated with the gate allowing the same to be swung into an active position.

2. In combination with an internal combustion engine having an intake manifold 100 and a pipe connecting the same with a carburetor, a means for closing said pipe comprising a housing formed integral with and extending laterally from the pipe so 105 as to communicate with the interior there- 110

- of, a gate hinged at the point of juncture between the housing and the pipe, a spring connecting the remote end of the gate with the far wall of the housing for normally maintaining the gate inactive and a handle associated with the gate allowing the same to be swung into an active position, said handle being disposed on the outside of the housing.
- 10 3. In combination with an internal combustion engine having an intake manifold and a pipe connecting the same with a carburetor, a means for closing said pipe comprising a housing formed integral with and extending laterally from the pipe so as to communicate with the interior thereof, and a gate hinged at the point of the juncture between the housing and the pipe formed to rest on the inner end of the housing when in an inactive position and to close the pipe when in an active position, yielding means being provided for normally maintaining the gate in an inactive position and a handle for swinging the same into an active position.
- 15

ing when in an inactive position and to close 20 the pipe when in an active position.

4. In combination with an internal combustion engine having an intake manifold and a pipe connecting the same with a carburetor, a means for closing said pipe 25 comprising a housing formed integral with and extending laterally from the pipe so as to communicate with the interior thereof, and a gate hinged at the point of the juncture between the housing and the pipe 30 formed to rest on the inner end of the housing when in an inactive position and to close the pipe when in an active position, yielding means being provided for normally maintaining the gate in an inactive 35 position and a handle for swinging the same into an active position.

LOUIS KAUFOLD.
